UNITED STATES PATENT OFFICE.

MARY F. HENDERSON, OF WASHINGTON, DISTRICT OF COLUMBIA.

DESIGN FOR A MOLD OR CUTTER.

SPECIFICATION forming part of Design No. 24,341, dated May 28, 1895.

Application filed April 18, 1895. Serial No. 546,274. Term of patent 14 years.

To all whom it may concern.

Be it known that I, MARY F. HENDERSON, a citizen of the United States, residing at Washington, District of Columbia, have invented and produced a new Design for a Mold or Cutter, of which the following is a specification, reference being had to the accompanying drawing, forming a part thereof, in which the figure represents a perspective view of my design for the mold.

The leading feature of my design consists of five pointed edges somewhat resembling in outline the leaves of a daisy meeting together, as shown.

The mold or cutter may be made of any material.

The form is designed to give to each egg when cooked in it the conventionalized resemblance of a daisy or marguerite, the egg yolk carrying out the design of the yellow center of the flower.

Having set forth the essentials of my invention, what I claim is—

The design for a mold or cutter as herein described and shown.

MARY F. HENDERSON.

In presence of—

ELLEN HARDIN WALWORTH,
JENNIE WHITE.
